ERADICATING IMPLEMENT

Gregory Sala, New York, N. Y.

Application February 18, 1949, Serial No. 77,246

5 Claims. (Cl. 120—36)

1

This invention relates to new and useful improvements in a combined writing and eradicating implement, and, more particularly, the aim is to provide a novel and valuable duo-fountain implement wherein one fountain serves a writing point and another fountain serves an eradicating point; the present utility especially in mind being the provision of an improved stenographic pen and eradicator.

According to the present invention a single article is provided, which may closely resemble an ordinary fountain pen, and which incorporates a single barrel having at one end a writing point and at its opposite end an eradicator point. Both fountains are inside said one barrel, but the barrel is separable into a plurality of sections at a point intermediate its ends to allow convenient refilling when such a refilling is required. Also, desirably, the new implement is provided with two readily removable caps, one at each end, and each for covering one of the points when the latter is not in use.

A feature of the invention is the subdivision of the barrel into three readily separable sections, these being preferably threadedly connected; with the middle section a rather short or ring-like section, and which may be uncoupled from the other two sections, thereby to free the section having the eradicator point from the other two sections. In this latter connection, means are provided whereby the eradicator fountain may be readily refilled.

Another feature of the invention is the provision of a bodily removable closing valve member for the filling end of the eradicator fountain, which valve member, in combination with a co-operating part carried by the section having the ink fountain and further in combination with a shaped internal portion of the ring section, restrains the fluid in the fountain last-named from accidental spill therefrom.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 elevationally shows a now favored embodiment of the new implement, with both caps applied to the barrel.

Fig. 2 is a similar view, but partially broken away and partially in section, with both the caps removed.

2

Fig. 3 is, on a somewhat enlarged scale, a view showing the ring section in diametral section.

Fig. 4 shows the implement elevationally, with both caps removed as in Fig. 2, and, further, with said ring section and the section for containing the eradicator fluid both removed.

Fig. 5 elevationally shows merely the section for containing the eradicator fluid, with the already mentioned valve member left in place.

Fig. 6 is an enlarged top plan view of said valve member.

Fig. 7 shows the same in side elevation.

Referring to the drawings more in detail, the barrel, as a whole designated 10, incorporates three threadedly connected sections 12, 14 and 15; the latter being the ring section. Section 12 at its tip carries a writing point 16, which may be of the long familiar split nib type or of the rolling ball type recently coming into rather wide use. The section 14 at its tip carries a suitable eradicator point 17, which also may be of the said split nib type or of said rolling ball type.

The ring section 15 has an axial bore therethrough which centrally is of slightly less diameter, as indicated at 18, than its upper and lower portions, where said bore is threaded as shown at 19 and 20. The thread 19 is for matching an external thread on a reduced lower extension 21 of the section 12, and the thread 20 is for matching an external thread on the reduced upper extension 22 of the section 14.

The ink fountain for the point 16 is within a cavitation 23 in the section 12; and the fountain of eradicating fluid for the point 17 is constituted by a cavitation 24 in the section 14.

Any desired means for refilling the said ink fountain may be included; but, as herein shown, a familiar type of suction effectuating rocker-arm 25 for use in such refilling is indicated in Fig. 2.

Projected below the lower end of the extension 21 depending from the section 12, and suitably there anchored, is a substantially hemispherical projection 26.

At the upper end of the reduced extension 22 at the top of the section 14, the filling opening for the cavitation 24 is shaped to provide a valve-seat for fluid-tight coaction with a bodily removable valve member 29, which latter has a central depression 30 in its disk-like top portion 31, this depression for seating the projection 26 when the parts are coupled as shown in Fig. 2. Then, as will be noted, said projection is received in the hollow portion 18 of the ring section 15.

as is also the said portion 31 of the valve member 29.

In addition to the barrel 10, the new implement is provided with a pair of separately readily removable caps 32 and 33; with, of course, the cap 32 to be temporarily removed when writing is to be done and the cap 33 to be temporarily removed when eradicating is to be done. As is conventional, the section 12 may be provided at a suitable point thereon, as at 34, with a tiny air-admission orifice. A similar orifice may be provided at a suitable point on the barrel 14; but, as herein shown, the air-admission means comprises an orifice 35 through the ring section 15 opposite the recess 18, and, in combination therewith, a suitably placed orifice, as indicated at 36, slantingly passing through the valve member 29. Thus, free use of either of the points 16 and 17 cannot be hampered by trapped air in its fountain.

In order to refill the cavitation 24 with eradicator fluid, it is merely necessary to unscrew the section 14, and lift from its seat the valve member 29, and then supply the said fluid as by the aid of a glass medicine dropper.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In an article having a main body section and a hollow outer section for containing eradicator fluid and having at its one end an eradicator fluid dispensing tip, an externally threaded extension extended concentrically from the end of the main body section facing the outer section, a tubular externally threaded extension extended concentrically from the other end of the outer section facing the main section and being in communication with the hollow of the outer section so that the supply of fluid in the outer section can be replenished, a ring section having internal threads extended in from each of its ends for receiving said threaded extensions to connect the main section and the outer section, said ring section being of a length greater than the combined length of said extensions so that a space is left between said extensions when threaded completely into said ring section, a valve positioned in said space for closing the outer end of said tubular extension, and means on said first extension pressing said valve into operative position against the end of said tubular extension when said extensions are threaded completely into said ring section.

2. In an article having a main body section and a hollow outer section for containing eradicator fluid and having at its one end an eradicator fluid dispensing tip, an externally threaded extension extended concentrically from the end of the main body section facing the outer section, a tubular externally threaded extension extended concentrically from the other end of the outer section facing the main section and being in communication with the hollow of the outer section so that the supply of fluid in the outer section can be replenished, a ring section having internal threads extended in from each of its ends for receiving said threaded extensions to connect the main section and the outer section,

said ring section being of a length greater than the combined length of said extensions so that a space is left between said extensions when threaded completely into said ring section, a valve positioned in said space for closing the outer end of said tubular extension, and means on said first extension pressing said valve into operative position against the end of said tubular extension when said extensions are threaded completely into said ring section, said means comprising a projection concentrically on the inner end of said extension of the main section and bearing against the adjacent face of said valve.

15. 3. In an article having a main body section and a hollow outer section for containing eradicator fluid and having at its one end an eradicator fluid dispensing tip, an externally threaded extension extended concentrically from the end of the main body section facing the outer section, a tubular externally threaded extension extended concentrically from the other end of the outer section facing the main section and being in communication with the hollow of the outer section so that the supply of fluid in the outer section can be replenished, a ring section having internal threads extended in from each of its ends for receiving said threaded extensions to connect the main section and the outer section, said ring section being of a length greater than the combined length of said extensions so that a space is left between said extensions when threaded completely into said ring section, a valve positioned in said space for closing the outer end of said tubular extension, and means on said first extension pressing said valve into operative position against the end of said tubular extension when said extensions are threaded completely into said ring section, said means comprising a projection concentrically on the inner end of said extension of the main section and bearing against the adjacent face of said valve, said valve comprising a disc-like top portion bearing against the end of said tubular extension, and a conical projection extending from said top portion into said tubular extension.

4. In an article having a main body section and a hollow outer section for containing eradicator fluid and having at its one end an eradicator fluid dispensing tip, an externally threaded extension extended concentrically from the end of the main body section facing the outer section, a tubular externally threaded extension extended concentrically from the other end of the outer section facing the main section and being in communication with the hollow of the outer section so that the supply of fluid in the outer section can be replenished, a ring section having internal threads extended in from each of its ends for receiving said threaded extensions to connect the main section and the outer section, said ring section being of a length greater than the combined length of said extensions so that a space is left between said extensions when threaded completely into said ring section, a valve positioned in said space for closing the outer end of said tubular extension, and means on said first extension pressing said valve into operative position against the end of said tubular extension when said extensions are threaded completely into said ring section, said means comprising a projection concentrically on the inner end of said extension of the main section and bearing against the adjacent face of said valve, said valve comprising a disc-like top portion bearing against

the end of said tubular extension, and a conical projection extending from said top portion into said tubular extension, said top portion having in its face opposed to the face from which said conical projection extends a depression seating said first projection.

5. In an article having a main body section and a hollow outer section for containing eradicator fluid and having at its one end an eradicator fluid dispensing tip, an externally threaded extension extended concentrically from the end of the main body section facing the outer section, a tubular externally threaded extension extended concentrically from the other end of the outer section facing the main section and being in communication with the hollow of the outer section so that the supply of fluid in the outer section can be replenished, a ring section having internal threads extended in from each of its ends for receiving said threaded extensions to connect the main section and the outer section, said ring section being of a length greater than the combined length of said extensions so that a space is left between said extensions when threaded completely into said ring section, a valve positioned in said space for closing the outer end of

said tubular extension, and means on said first extension pressing said valve into operative position against the end of said tubular extension when said extensions are threaded completely into said ring section, said ring section and said valve being formed with passages for venting the interior of the hollow section to prevent air locking of the fluid contained in the hollow section.
